UNITED STATES PATENT OFFICE.

OLOF AKERBERG, OF EVERETT, WASHINGTON.

ROTARY ENGINE.

No. 833,107.

Specification of Letters Patent.

Patented Oct. 9, 1906.

Application filed April 11, 1905. Serial No. 254,912.

To all whom it may concern:

Be it known that I, OLOF AKERBERG, a citizen of the United States, residing at Everett, in the county of Snohomish and State of Washington, have invented certain new and useful Improvements in Rotary Engines; and I do hereby declare the following to be a full, clear, and exact description of the invention, such as will enable others skilled in the art 10 to which it appertains to make and use the same.

This invention relates to certain new and useful improvements in rotary engines.

One of the numerous objects in view is the 15 improvement of the general construction of an engine which may be operated by means of the expansion of steam, gas, or compressed air.

Another object of the invention is the improvement of the construction of a rotary piston, a casing inclosing the same, and valve means coacting with said pistons.

A still further object of the invention is the 20 production of a mechanism which comprises a minimum number of parts and which is durable and comparatively inexpensive in construction and efficient in operation.

While I have mentioned some of the objects of the invention, the same includes certain other novel constructions, combinations, and arrangements of parts, as will be herein-after fully described, illustrated in the accompanying drawings, and more particularly pointed out in the claims hereto appended.

In the drawings, Figure 1 is a view in front elevation of a mechanism constructed in accordance with the present invention. Fig. 2 is a view in side elevation of the mechanism shown in Fig. 1, partly illustrated in vertical section. Fig. 2^a is a horizontal sectional view of the guiding-rod, to which is secured the expansible receptacle. Fig. 3 is a fragmentary transverse sectional view of the mechanism illustrated in Fig. 1. Fig. 4 is a 35 fragmentary longitudinal sectional view of another embodiment of my invention. Fig. 5 is a fragmentary view, in side elevation, of another embodiment of the present invention, partly shown in longitudinal vertical section. Fig. 6 is a view in side elevation of another embodiment of the invention, partly shown in section. Fig. 7 is a horizontal sectional view taken on line 7 7, Fig. 2.

Referring to the drawings by numerals, 1

designates stationary standards which are 55 provided for supporting the double cylindrical casing 2. The cylindrical casing 2 is provided with laterally-extending lugs 3, which are positioned upon the upper portion of the standards 1. The casing 2 is provided 60 with double walls, forming a compartment 4. The compartment 4 forms a receptacle within which water or any suitable cooling means may be stored.

Extending upon one side of each of the 65 casings 2 is a journal-box 5. A drive-shaft 6 is journaled centrally within the casings, and within each of the casings 2 and secured to the shaft 6 is a revoluble piston-carrier 7. The piston-carrier 7 is provided with a pair 70 of pistons 8. Said pistons 8 are provided upon each side with integral webs or extensions 9, which constitute cams for raising the movable abutments 10, which are pivotally mounted within the casing 2 and secured 75 to shafts 11. The shafts 11 are each provided exteriorly of their respective casings with a crank-arm 12.

The movable shoes or oscillatory abutments 10 are each positioned within an enlarged portion 12', formed upon the casing 2 at diametrically opposite points. It will be seen upon referring to Fig. 3 that the pistons 8 are substantially rectangular in shape, and they are integrally connected to the hub 80 portion of the piston-carrier by means of a reduced portion 13. The inner wall of each of the casings is provided with an integral annular extension 14 upon each side thereof, which is normally engaged by a movable 85 packing 15, positioned within the grooves of the reduced extension 13 of the piston-carrier upon each side thereof. The packings 15 are held against the annular extensions 14 of each of the casings by means of springs 16. 90 Upon the wall-engaging surfaces of each of the pistons 8 there are formed grooves, within which are positioned movable packings 17 and 18. The packings 17 and 18 are held 95 against the inner wall by means of springs 19. Each abutment 10 is provided upon its sides with curved ribs 10^a, constituting packings, which packings engage the sides of the primary casing of the engine. In the present instance I have shown two of the casings 2 secured together, each casing being formed upon one side with an annular recess 20, which communicates with the compartment 100 105

4, formed by the inner and outer walls of the casing 2. When the two casings are secured together, there is formed a comparatively large compartment produced by the recessed portions 20 of said casings, as will be clearly seen upon referring to Fig. 3. The annular recessed portion 21 is formed upon the inner face of the hub portion 5, which may be filled with a suitable lubricant for lubricating the revoluble shaft 6.

A pair of cylindrical compartments are formed upon the upper portion of each of the casings 2, within which are mounted cylindrical-shaped revoluble valves 22. Each of said valves 22 is provided with a series of elongated apertures 23. Each of the valves 22 is closed at the outer end 24 by means of an integral extension 25. A ratchet-wheel 26 is secured to the extension 25 of each of the valves 22. While the end 24 of the valves 22 is closed by the integral extension 25, the opposite end is opened for permitting the passage of steam, gas, or air through said valve from the inlet-pipe 27. The inlet-pipes 27 in the embodiment disclosed in Figs. 1 to 4 communicate with the intermediate storage-receptacles 31. A port 29 is formed in the casing 2 near each of the valve-compartments for providing communication between the hollow portion of each of the valves 22 and the recessed portion 30 of the movable abutments 10. When one of the openings 23 of the movable valve 22 registers with the transverse opening constituting the port 29, direct communication is had between the inlet-pipe and the compartment formed in the casing between the movable abutment 10 and one of the pistons 8. Each of the shoes or oscillatory abutments 10, which are movably mounted upon the casing, is provided with packings 17, which are employed for making tight joints or connection between the inner wall of the respective casing and said abutment. It will be noted that the recessed portion 30 is not of the same length as the width of the face of said abutment in order that when the abutment is moved to the position clearly shown in Figs. 2, 4, and 5 communication between the valve 22 and the compartment formed between the face of the abutment 10 and one of the pistons may be obstructed by a portion of said abutment.

Referring more particularly to Fig. 2, it will be seen that there is positioned upon the primary casing 2 an intermediate storage or auxiliary receptacle or casing 31, within which is secured a movable sack 32. The sack 32 comprises in its construction a flexible casing 33, to which is secured upon the upper portion thereof an apertured metallic plate 34. The apertured portion of said metallic plate is closed by a flap-valve 35. The lower portion of the flexible sack is fixedly secured to the bottom portion of the casing 31. The flexible sack may be formed of rub-

ber, silk, or any analogous material which will permit of the expansion and contraction of said sack.

The intermediate receiving or fuel receptacle 31 is provided with an aperture 36, which is normally closed by a flap-valve 37. The receptacle 31 is connected with any suitable reservoir by means of a valved tubing 38. The valve member 39 of said tubing 38 is provided for regulating the supply of liquid, which is preferably gasolene, to the casing 31. The casing 31 is provided with a compartment 40, formed upon one side thereof, said compartment communicating with the upper portion of the chamber 80 formed within the casing 31 and the interior of the sack 32. A valve member 41 is mounted upon casing 31 for controlling the pressure of the gas, which is supplied to the casing 2 through the inlet-pipes 27.

By adjusting the valve member 41 the size of the opening at the bottom of compartment or by-pass 40 may be controlled. If the valve member 41 is nearly removed from casing 31, the passage of gas from within the expansible receptacle through by-pass 40 into the compartment in receptacle 31 will not be obstructed. The adjusting of valve member 40 will consequently control the amount of gas which is passed into the explosive chambers 95 of the engine through the medium of either of the pipes 27. The inlet-pipes 27 communicate with the compartment formed in the casing 32 through the aperture 42 of the casing 31. For preventing gas from being forced back 100 into the chamber 32 after the same has been forced into the inlet-pipes 27 I provide flap-valves, as is, for instance, shown at 27'. The flap-valves swing downwardly and are held in position normally by any suitable 105 means—as, for instance, the spring 27a.

A hollow vertically-movable rod 43 is journaled in the casing 31 and is connected to the valve-actuating mechanism carried by the casing. The vertical movable rod 43 is provided with a plurality of apertures 44 and ribs 44', which permit of the passage of a suitable lubricant from the compartment formed by the hollow structure of said rod to the exterior surface of the rod 43. The metallic plate 34 is secured to the rod 43. When reciprocatory movement is imparted to the rod 43 through the medium of the valve-actuating mechanism the flexible casing will be alternately expanded and contracted. 115 Oil is supplied to the auxiliary casing 31 through the pipe 38, as well as atmosphere through the valved aperture 36. The oil and atmosphere contained in the auxiliary casing are permitted to pass into the casing 32 120 as the same moves to the position shown in broken lines, Fig. 2, as the flap-valve 35 will not be retained in the position indicated in said figure when the casing 32 is being expanded by upward movement of rod 43. 125 130

As the rod 43 moves downward the gas contained in the casing 32, formed by the commingling of the oil and atmosphere in the casing 31, is forced into the respective inlet-pipe 27. If it is desired to decrease the speed at which the engine is running or to cut off the supply of gas to a certain degree which is being fed to the explosive compartment of the casing 2, this can be accomplished by adjusting the valve member 41. If the valve member 41 is opened to its greatest extent, as the expansible casing 32 is contracted a large amount of the gas contained therein will be forced through the compartment or by-pass 40 into the compartment formed by the casing 31 exteriorly of the expansible casing 32. The valve-actuating mechanism which imparts movement to the rod 43 in timed relation to the movement of the valve will be hereinafter specifically described.

The movement of the engine in one direction can be easily reversed by moving a lever 46, which is movably mounted upon an integral extension 47, formed upon one side of the casing 2. The sides of the casing 2 comprise removable plates, which are retained in their normal position by means of a series of transverse bolts 48. The bolts 48 extend through apertured portions formed in the sides and between the inner and outer walls of the casing within the compartment 4. By reason of this sectional structure of the casing it is exceedingly simple to remove the sides of the casing or cylinder if it is desired to examine or repair any of the mechanism inclosed by the casing 2. Upon each side of the transverse aperture constituting the port 29 are positioned spring-pressed packings 49 and 50. The packing 50 is removably positioned in its respective recess or groove by means of a screw 51. A recess or transverse grooved portion 52 is formed in the casing near each of the valves 22. These recesses 52 are provided for receiving the integral extensions 53 of the abutments 10 when each of said abutments is moved within the bulged portion 12' of the casing 2, as is shown in the right-hand side of Fig. 4, for permitting of the free movement of the pistons 8.

Each of the bulged portions 12' of the casings is provided upon its upper portion with a removable standard or support 54. Pivotaly mounted upon the upper end of each of the standards 54 is a movable arm or bar 55. The bar 55 is provided with an elongated slot 56 and with an integral lateral extension 57. A link 58 connects the crank member 12 and the movable bar 55 through the medium of the lateral extension 57 and the similar extension 59, which is formed upon crank 12. When movement is imparted to the crank member 12, similar movement of the arm 55 will be caused. A

parallel movable arm 60, which is provided with a lateral extension 61, is supported upon the pivotally-mounted arm 55. The parallel member 60 is provided with a bifurcated end 62. The bifurcated or notched end 62 of the bar or parallel member 60 provides means whereby the same may be removably secured to the pin or lateral extension 63 of the vertically-movable rod 43. The movable arms or bars 60 are each provided with an arm 64, to which the lever 46 may be secured when the same is swung to a vertical position.

Referring particularly to Fig. 7, it will be seen that the arm 64 is positioned upon the extension 61, which is preferably a bolt or rivet, and said arm 64 is capable of being secured in a longitudinal adjusted position by positioning one of its notched portions 64^a upon the pin 64^b, carried by the standard 54. By unhooking the arm 64 the member 60 may be adjusted longitudinally for either connecting or disconnecting the same with the stud or lateral extension 63 of member 43.

A coiled spring 65 is secured at one end to the shaft 11, and its opposite end engages a portion of shaft 47. The spring normally exerts downward pressure upon the crank member 12 for holding the abutment 10 in an operative position. The inner end of each of the levers 46 is provided with an antifriction-roller 66, which engages the lower surface of one of the crank members 12. As soon as the lever 46 is moved to a vertical position the crank member 12 will be swung down, causing the abutment carried by the shaft 11, to which the respective crank member is secured, to be moved downwardly within the casing 2. During part of the travel of said abutment the recessed portion 30, through the medium of the port 29, will provide direct communication between the inlet-pipe 27 and the cylinder through the valve member 22 by reason of the fact that one of the ports 23 of said valve will register with the port 29. Before the abutment 10 has been moved to its lowest position within the casing 2 the port 29 is closed, and subsequently the piston passes the exhaust-port 67, permitting of the gas to be exhausted to the outer atmosphere.

The ratchet-wheel 26 is retained against movement in one direction by means of the pawl 68. Pawls 69 and 70 are mounted upon the link 58, and a spring 71, which is provided with two angular ends, is mounted upon the link member 58 and engages each of the pawls 69 and 70. A pawl 72 is secured upon an extension 73 of the crank member 12 and is retained in its normal position by means of a spring 74. A pawl 75 is secured upon the opposite end of crank member 12 to pawl 72 and is retained in its normal position by means of a spring 76. When the crank member 12 moves downwardly through the

action of spring 65, the abutment 10 will pivot downwardly by means of its own weight, and spring 65 and pawl 70 will impart rotary movement to the ratchet-wheel 26 and thereby rotate valve 22, causing one of the ports 23 to register with the port 29, permitting of the passage of gas into the casing 2, between the face of the abutment 10 and one of the pistons. As the abutment continues its downward movement pawl 69 will rotate the valve 22 and close port 29. Synchronously with the closing of the port 29 pawl 75 will engage one of the movable arms 77, causing said arms to close together, closing the circuit at points 78 and through the medium of electrical means 79 and 80 the gas contained in the casing 2 will be ignited. Specific description of the sparking plug 80 is not necessary, as I do not make any specific claim to the structure of said plug and electrical means coacting with the movable spring-pressed arms 77, as this structure is known to the art. The substantially U-shaped member 81, provided with outward resilient arms, normally retains the members 77 apart. Outward movement of arms 77 is limited by means of lugs 79, constituting stops. These lugs are carried by the primary casing contiguous to the arms 77.

The embodiment shown in Fig. 4 is very similar in most of the details to the structure shown in Figs. 1, 2, and 3, the difference in the structure shown in Fig. 4 being in the expandible receptacle-containing casing 82.

The integral threaded extension 83 extends upwardly from each of the bulged portions 12'. Said integral extension 83 is provided with a central aperture. An expandible receptacle 84 is positioned within the casing 82. The chamber 84', formed within the receptacle 84, may be placed in communication with the compartment of the bulged portion 12' of the casing 2 by means of the apertured structure of the extension 83. The casing 82 is provided with ports 85. Valved inlet-pipe 38' permits oil to be supplied to the interior of the receptacle 84.

In the embodiment illustrated in Fig. 2 through the medium of the rod or member 43 the expandible receptacle is compressed for forcing the gas through the inlet-pipe into the casing; but in the embodiment depicted in Fig. 4 I preferably employ the spring 84^a. Atmosphere is introduced into the receptacle 84 from the compartment 86, formed in the bulged portion 12'. Atmosphere is introduced into the compartment 86 through a port closed by valve 86^a. A flap-valve similarly constructed to valve 86^a closes the upper end of the apertured portion 87. A recess 86' is formed upon one side of the abutment 10 for receiving the flap-valve 86^a when the abutment is in the position shown on the right in Fig. 4. An inlet-pipe 27 provides direct communication between rotary valve

22 and the interior of the expandible receptacle 84. As the abutment moves downwardly air is drawn into the compartment 86, and subsequently as said abutment moves upwardly the atmosphere contained in this compartment is forced into the expandible receptacle 84. The valve member 41^a controls the supply of liquid through pipe 38' to receptacle 84. In Fig. 2 I have shown a valve member 39 for controlling the supply of gasolene to the explosive chamber, while in Fig. 4 a valve member 41^a is employed for a similar purpose. In the structure depicted in Fig. 4 the port or channel 41^c is not placed in communication with receptacle 84 for allowing of the exhaust of air therein; but in this instance the air is exhausted into the outer atmosphere.

When it is desired to employ steam as the motive power for operating the engine, it will only be necessary to remove a few of the parts, as illustrated in Fig. 5. Instead of the inlet-pipes 27, which are employed for introducing gas into the engine, steam-pipes 88 are connected with the valves 22, the pawl 70 being removed from the link 58 and the exhaust-port 67 being closed by means of a removable cap 89. The exhaust of the dead steam to the outer atmosphere is permitted through the exhaust-port 90. After the lever 46 has been moved to its vertical position and the ratchet-wheel 26 revolves for opening the port 29 live steam from the inlet-pipe 88 will be discharged into the cylinder of the casing 2 against one of the abutments 10 for imparting movement to the rotary piston. As the piston revolves and comes in contact with the lower face of the abutment 10 and raises the same the crank-arm 12 will also be swung on its pivot, and the pawl 72 when traveling upwardly to the position shown in Fig. 5 will come in contact with the ratchet-wheel 26 and close the port. In other words, pawl 69 is used for opening the port, while pawl 72 is the means for closing the same. Of course arms 77 and the pawl 75 shown are not employed when using steam as the motive power for actuating the piston.

Instead of employing the exhaust-ports 67 exhaust-port 90 is employed. The exhaust-port 90 is in communication with ports or channels 91, 92, and 93. Gas or steam may be discharged into the chamber or compartment 86 of the bulged portion 12' or through channels 91 and 93. It will be seen that the port or channel 92 will be closed when the abutment 10 is positioned against the piston. Upon the downstroke of the abutment 10 the passage or port 92 will permit of the discharge of the dead steam into the space between the abutment and piston to allow said space to be filled with steam. Before the new charge of live steam enters the engine the passage or port 93 permits steam to be

discharged into the compartment 86 to remove any resistance below the abutment. When the abutment has moved to its lowest position, the port or passage 92 will be closed and passage 90 opened to permit of the remaining dead steam to pass into the outer atmosphere, the object of this structure being the saving of steam or gas, as the case may be.

In Fig. 6 I have illustrated another embodiment of the invention which is particularly adapted for employing steam as a motive power. While the casing in this instance is not provided with double walls, the general structure is similar to the other embodiments; but there are some details which I will specifically describe. I will only describe the structure of one of the valves and its coacting mechanism, as the valves and their coacting mechanisms are duplicates.

A steam-pipe 88 communicates with the interior of the rotary valve 22'. The rotary valve 22' is provided with a single port 26. In this embodiment, in place of the ratchet-wheel 26, I employ a member 97, which is fixedly secured to the extension 98 of the valve 22'. Formed upon the shank 12 is an extension 99, which is adapted to engage the tooth 100, formed upon member 97, for causing the port 96 in the rotary valve 22' to register with the port 29 for permitting of the passage of steam into the cylinder. In assuming its uppermost position the crank 12, through the medium of the spring-pressed pawl 101, will engage the extension 102 of member 97 and close the port 29. If it is desired to close the port 29 before the crank has moved to its lowest position, this may be accomplished by positioning the removable toothed member 103 upon said crank. The tooth or member 103 is adapted to engage the tooth 100 of member 97. It will be seen that upon slight movement of the crank 12, through the medium of tooth 100 and the tooth formed upon member 103, that port 29 will be closed. Upon the shaft 6 and outside of the journal-box 5 is movably secured a ring 104, which is provided with extensions 105, carrying inwardly-projecting pins 106. Upon the extension 107, which is secured to the end of the casing, I position a swinging arm 108. The lower end of the arm 108 is engaged by the extensions 106 to turn said arm on its pivot. At each half-revolution of the shaft 6 one of the extensions 106 will engage the lower end of the arm 108 and force one of the slideable pins 109 longitudinally within the fixed boxes 110. Each of the pins 109 is adapted to engage the tooth 100 of member 97 for moving member 97 and causing the port 96 of valve member 22' to register with the port 29. A spring 111 is fixedly secured, by means of an annulus 112, to the extension 107. The upper free end of the spring 111 is positioned between two studs or extensions 113, carried

by swinging arm 108. The object of the spring 111 is to return the arm 108 to its normal vertical position after movement thereof. A stud 114 is employed for limiting rotary movement of member 97. A yielding strip of material, as 115, may be secured upon the piston to reduce the blow of the abutment against said piston-carrier as said abutment engages the same.

In this specification I have described specifically the structure of one of the abutments 10 and its coacting mechanism.

It will be obvious from the foregoing description that each of the casings and the mechanism carried thereby constitute a separate engine and that in each of the engines there is employed two of the abutments and their coacting mechanism for permitting the engine to be reversed.

It would be superfluous to specifically describe the mechanism upon each end of the engine in each embodiment, as they are similar in structure and operate in the same manner.

Apertures 94 are formed in the sides of the casing for permitting the piston to be lubricated.

Any number of the engines may be connected to a single drive-shaft.

Referring particularly to the embodiment 95 depicted in Figs. 1 to 3, when one of the levers 46 is moved outwardly, thereby raising the crank-arm 12 to the position shown in Fig. 2, this will permit the engine to operate in one direction, while upon swinging the same lever upwardly to a substantially vertical position, thereby permitting the crank-arm 12 to be lowered and at the same time lowering the other lever 46, so as to raise its crank-arm 12 and abutment 10, the engine 105 will be permitted to operate in a reverse direction to that of its first movement. This is true of the mechanism in all of the embodiments. In other words, when one of the crank-arms is raised through the means 110 of a lever the other crank-arm should be lowered, as it is absolutely necessary that one of the abutments should be in an operative position, while the other abutment is in an inoperative position. An abutment is in an operative position when in engagement with the piston-carrier, as clearly depicted in Fig. 2. An abutment is in an inoperative position when positioned entirely within one of the bulged portions of the casing, as, for instance, will be clearly seen upon referring to Fig. 4. As the piston-carrier revolves the abutment 10, which is in the path of movement of the pistons 8, will be swung from the position shown in Fig. 2 into the 120 bulged portion of the casing, and as said piston passes the abutment the same will swing back into its engaging position with the piston-carrier. Therefore it will be seen that if its crank-arm 12 is suitably connected to 130

the vertically-movable rod 43 movement will be imparted to said rod, which, owing to the fact that plate 34 of the expansible receptacle 32 is fixedly secured to said rod, will 5 cause expansion and contraction of said receptacle. The means for connecting each of the crank-arms 12 with the vertical slidable rod 43, through the medium of the lug or extension 63, comprises links 58, bars 55, and 10 movable arms 60. When one of the arms 60 is shoved against the lug or extension 63, said lug is positioned within the bifurcated portion 62 of the arm 60. When the link 58 is moved vertically, the arm 60 will move the 15 rod 43, thereby operating the expansible receptacle. One of the valves 22 will be synchronously moved when one of the crank-arms 12 is actuated by means hereinbefore described. This synchronous movement of 20 the valve 22 opens and closes the ports in time relation with the movement of the piston-carrier and its pistons, so that gas or steam, whichever may be employed for driving the piston-carrier and pistons, will be 25 permitted to pass through the ports into the chamber formed within the primary casing.

Having thus fully described my invention, what I claim as new, and desire to secure by Letters Patent, is—

30 1. In a mechanism of the class described, the combination of a double-walled, primary casing, a rotatable piston mounted within said casing, said casing provided with bulged portions, an oscillatory abutment positioned 35 within each of the bulged portions of said casing, a rotatable valve journaled in said casing near each of the bulged portions; an auxiliary casing secured to said primary casing, an expansible receptacle contained within 40 said auxiliary casing, means connecting said valves and auxiliary casing providing communication between the interior of said expansible receptacle and the primary casing, and an actuating mechanism coacting 45 with said expansible receptacle, valves, and abutments.

2. In a mechanism of the class described, the combination with a primary casing, of a 50 revoluble piston mounted within said casing, oscillatory abutments carried by said casing, valve means formed upon said casing contiguous to each of said abutments, an expansible receptacle carried by said casing, and means for supplying gas from said receptacle 55 to the valve means, when said receptacle is compressed, an actuating mechanism coacting with each of said valves and abutments and with said expansible receptacle, said mechanism comprising a crank-arm secured 60 to said abutment, a vertically-movable rod connected to said expansible receptacle, and removable means connecting said rod to said crank-arm.

3. In a mechanism of the class described, 65 the combination with a casing, and a revolu-

ble piston mounted therein, of oscillatory abutments journaled in said casing, an expansible receptacle carried by said casing, means connecting said expansible receptacle to said casing and providing direct communication between the interior of said receptacle and casing, and means for expanding and contracting said receptacle, comprising a crank-arm secured to an abutment, a movable link secured to said crank-arm, a pivotal arm secured to said casing and connected to said link, an adjustable arm carried by said pivotal arm, a vertically-movable rod secured to said expansible receptacle, means for connecting said rod to said adjustable 70 arm.

4. In a mechanism of the class described, the combination with a primary casing, of a piston mounted within the same, oscillatory abutments journaled in said casing, an auxiliary casing mounted above said primary casing, an expansible receptacle contained within said auxiliary casing, a revoluble valve journaled in said casing near each of said abutments, tubing connected to said 85 auxiliary receptacle and primary casing and providing direct communication between the interior of said expansible receptacle and valve, an actuating mechanism for each of said valves and coacting with said expansible 90 receptacles, comprising a crank-arm on an abutment, a link secured to said crank-arm, a hollow rod connected to said expansible receptacle, said rod having an aperture formed therein, an extension formed integrally upon said rod, an adjustable means engaging said extension and assembled with 95 said link.

5. In a mechanism of the class described, the combination with a primary casing, a 100 revoluble piston mounted within said casing, valve means carried by said casing and coacting with said piston, of an auxiliary casing carried by said primary casing, an expansible receptacle mounted within said auxiliary casing, a mechanism connected with 105 said valve means and expansible receptacle and capable of synchronously actuating said valve and moving said receptacle, said mechanism comprising a crank member, a spring secured to said crank member and normally 110 exerting downward pressure upon the same, and link means connected to said crank member and expansible casing.

6. In a mechanism of the class described, 115 the combination with a casing, of a revoluble piston mounted therein, said casing provided with bulged portions, an oscillatory abutment positioned within each of said bulged portions, valve means formed upon 120 said casing contiguous to each of said abutments, means for actuating said abutments and valves in timed relation, an expansible receptacle carried by said casing and communicating with the valve means, and means 125 130

for compressing the contents of said expandable receptacle.

7. In a mechanism of the class described, the combination with a primary and an auxiliary casing, a piston mounted within said primary casing, an expandible receptacle positioned within said auxiliary casing, oscillatory abutments journaled within said casing, a revoluble valve journaled within said casing contiguous to each of said abutments, and tubing connecting said valves and expandible receptacle, means for controlling the pressure in the expandible receptacle, when the same is compressed, valved means for supplying liquid and atmosphere to said auxiliary casing, a mechanism for actuating one of said valves, and expandible receptacle, comprising a pivotally-mounted lever, a bearing journaled upon one end of said lever, a crank member secured to said abutment, a ratchet-wheel secured to said valve, a pawl engaging said ratchet-wheel, a link member secured to said crank-arm, pawls carried by said link member, cushioning means engaging said pawls, a standard secured to said primary casing, an arm pivoted to said standard, means connecting said arm and link, an adjustable, bifurcated member secured to said arm, a hollow, perforated rod provided with guiding-ribs, secured to said expandible receptacle, said rod provided with an integral extension formed near its lower end, said extension adapted to be positioned within the bifurcated portion of the adjustable member, and means for removably securing said lever to said adjustable member.

8. In a mechanism of the class described, the combination with a primary casing, of a revoluble piston mounted therein, an auxiliary apertured casing positioned upon said primary casing, valve means carried by said primary casing, connecting means for said valve means and auxiliary casing, said auxiliary casing provided with valved means for permitting atmosphere to be supplied to the interior thereof, an expandible receptacle positioned within said auxiliary casing, valve means for controlling pressure within said expandible receptacle, when the same is compressed, and means connecting said expandible receptacle to the valve means carried by the primary casing.

9. In a mechanism of the class described, the combination of a casing, said casing comprising double, cylindrical walls and removable sides, an annular extension integrally secured to each of the sides of said casing and extending inwardly, a shaft journaled in said casing, a piston-carrier secured to said shaft, said piston-carrier provided with pistons, flanges, constituting cams, secured to said piston-carrier and pistons, packing means positioned upon the edges of said pistons, oscillatory abutments journaled in said casing, a revoluble valve journaled in said

casing contiguous to each of said abutments, means for supplying gas to said valve and casing, and lever and link means for controlling movement of each of said abutments and valves.

10. In a mechanism of the class described, the combination with a casing, a revoluble piston positioned within said casing, oscillatory abutments secured in opposite parts of said casing, a pair of revoluble valves journaled upon said casing, an expandible receptacle carried by said casing, and link and lever means carried by said casing and coacting with said oscillatory abutments, valves and the expandible receptacle for controlling movement thereof.

11. In a mechanism of the class described, the combination of a double-walled casing, said casing provided with bulged portions, an oscillatory abutment secured within each of said bulged portions, a revoluble valve journaled in said casing contiguous to each of said abutments, a revoluble piston-carrier, said piston-carrier comprising a hub portion, pistons extending from said hub portion, flanges, constituting cams, extending upon opposite sides of said pistons, standards extending from said casing, a movable arm secured to each of said standards, a crank member secured to each of said abutments, a link connecting each of said arms and crank members, a spring-pressed pawl secured to each of said links, a ratchet-wheel secured to each of said valves, levers secured to said casing, and a spring carried by said casing and engaging each of said crank members and levers.

12. In a mechanism of the class described, the combination of a double-walled casing provided with removable sides, a revoluble piston journaled in said casing, a pair of oscillatory abutments journaled in said casing, a pair of revoluble valve members journaled in said casing contiguous to said abutments, a pair of mechanisms for actuating said abutments and valve members, each of said mechanisms comprising a lever, a crank member secured to an abutment, a ratchet-wheel secured to the valve member, a pawl carried by said crank member, a link secured to said crank member, and a pawl carried by said link.

13. In a mechanism of the class described, the combination with a casing, a revoluble piston mounted within said casing, of a pair of oscillatory abutments journaled in said casing contiguous to said abutments, valves journaled in said casing contiguous to said abutments, pawl-and-ratchet means assembled with each of said valved and crank members for controlling movement thereof, and levers normally in engagement with said crank members and capable of controlling movement of the abutments and valve members for reversing the engine.

14. In a mechanism of the class described, the combination with a casing, a piston mounted therein, of oscillatory abutments journaled in said casing, valve means carried by said casing contiguous to said abutments, separate means for controlling movement of each of said abutments and valve means, and lever means coacting with said abutment and valve means and capable of controlling movement of the same for reversing movement of the piston.
15. In a mechanism of the class described, the combination with a casing, a revolute piston mounted within said casing, of oscillatory abutments journaled in said casing, valve means carried by said casing, a spring connected to each of said abutments and normally holding the same in an operative position, and levers carried by said casing and coacting with said abutments for holding the same in an inoperative position.
16. In a mechanism of the class described, the combination with a casing, of a revolute piston mounted within said casing, of a pair of oscillatory abutments journaled in said casing, valve means carried by said casing and coacting with each of said abutments, means for controlling movement of each of said abutments and valve means, and levers secured to said casing contiguous to said abutments and valve means for moving the same to an inoperative position.
17. In a mechanism of the class described, the combination with a casing, of a piston mounted within said casing, oscillatory abutments positioned within said casing and coacting with said piston, valve means carried by said casing, an auxiliary or fuel casing secured contiguous to said primary casing, a flexible sack or receptacle positioned within said auxiliary casing, and lever-controlled, separate means connecting said abutments and flexible receptacle, and being capable of controlling the movement of said valve means.
18. In a mechanism of the class described, the combination with a primary casing, of a piston mounted within said casing, abutments positioned within said casing and coacting with said piston, of an auxiliary or fuel casing secured contiguous to said primary casing, an expandible receptacle positioned within said auxiliary casing, and lever-controlled means for actuating said abutments and expandible receptacle.
19. In a mechanism of the class described, the combination with a primary casing, a revolute piston positioned within said primary casing, oscillatory abutments positioned within said casing, valve means carried by said casing, of crank-arms secured to said abutments, and separate levers coacting with said crank-arms, capable of being swung for moving said crank-arms and abutments and thereby controlling movement of said valve means.
20. In a mechanism of the class described, the combination with a primary casing, a revolute piston mounted within said casing, of oscillatory abutments positioned within said primary casing and capable of being positioned against said piston, valve means carried by said primary casing contiguous to each of said abutments, a crank member secured exteriorly of said primary casing and to each abutment, means formed upon said valve means and crank member for moving said valve means when movement is imparted to said crank member, and a lever secured contiguous to each of said crank members, said levers capable of moving said crank members and abutments to an inoperative position.
21. In a mechanism of the class described, the combination with a primary casing, of a revolute piston positioned within said casing, of oscillatory abutments provided with extensions positioned within said casing, the extensions of said abutments being capable of engaging the revolute piston, valve means carried by said casing contiguous to each of said abutments, a crank member fixedly secured to each of said abutments, means carried by said valve means and crank members, for actuating said valve means when movement is imparted to said crank members, and levers carried by said casing and coacting with said crank members and thereby lifting said abutments to an inoperative position and holding the same in said position.
22. In a mechanism of the class described, the combination with a primary casing, of a rotatable piston mounted within said casing, an oscillatory abutment positioned within said casing, an extension formed upon said abutment, the extension of said abutment adapted to normally engage said piston, valve means carried by said casing contiguous to said abutment, a crank member connected to said abutment, means formed upon said valve means and capable of being engaged by said crank member for imparting movement to said valve means, and lever means carried by said casing and normally in engagement with said crank member and capable of moving said crank member to and holding it in an inoperative position and thereby actuating said valve means.
23. In a mechanism of the class described, the combination with a casing, of a revolute piston mounted within said casing, of a swinging abutment provided with an extension positioned within said casing, the extension of said abutment adapted to normally engage said piston when the mechanism is in an operative position, a rotatable valve carried by said casing contiguous to said abutment, said casing and valve provided with communicating ports, means connected to said valve and said abutment and capable of actuating said valve for closing said ports when said abutment is moved to an inoperative position.

tive position, and lever means carried by said casing and capable of moving said abutment to an inoperative position.

24. In a mechanism of the class described, the combination with a primary casing, a rotatable piston mounted within said casing, a swinging abutment positioned within said casing, a rotatable valve carried by said casing contiguous to said abutment, an auxiliary or fuel casing carried by said primary casing, means connecting said fuel and primary casings in a communicating position, a flexible, compressible receptacle positioned within said auxiliary casing, and lever means for controlling movement of said valve and being capable of holding said abutment in an inoperative position.

25. In a mechanism of the class described, the combination with a primary casing, a pis-

ton mounted within said casing, a swinging abutment positioned within said casing, a valve carried by said casing contiguous to said abutment, said valve and casing provided with communicating ports, of means connected to said valve and said abutment and being capable of actuating said valve for closing said ports when said abutment is moved to an inoperative position, and lever means carried by said casing and being capable of moving said abutment to an inoperative position or permitting said abutment to move to an operative position.

In testimony whereof I affix my signature in presence of two witnesses.

OLOF AKERBERG.
